UNITED STATES PATENT OFFICE.

HANS C. HANSON, OF ALBERT LEA, MINNESOTA, ASSIGNOR TO AMERICAN GAS MACHINE COMPANY, OF ALBERT LEA, MINNESOTA, A CORPORATION OF MINNESOTA.

OVEN FOR CAMP STOVES.

Application filed August 10, 1925. Serial No. 49,473.

This invention relates to a camp stove structure and particularly to such a structure comprising an oven adapted to be collapsed and packed into small space with the stove and adapted to be held in several operative positions. Camp stoves of the type disclosed herein are now used in immense numbers and it is desirable to have an oven in connection therewith so that various baked articles may be cooked by the stove.

It is an object of this invention, therefore, to provide an oven comprising a plurality of connected plates which can quickly and easily be arranged to form an oven over the stove casing and which can easily and quickly be collapsed and folded together in very small space with the stove.

It is a further object of the invention to provide a camp stove having a casing with a collapsible oven, which oven may be disposed on and above the stove in cooking position or may be swung rearward and disposed at the rear of the stove to form a warming oven, means being provided for supporting the stove in said latter position.

It is still another object of the invention to provide a camp stove having a casing with a collapsible oven, one wall of which together with the end portions, is adapted to be arranged as a wind shield, said casing being provided with means for holding said end portions in position to form a wind shield.

It is also an object of the invention to provide a camp stove comprising a casing having a collapsible oven in connection therewith together with a collapsible heat distributing plate adapted to be disposed in said oven when in operative position and adapted to be collapsed and folded into small space with said oven when the latter is in collapsed and packed condition.

These and other objects and advantages of the invention will be fully set forth in the following description made in connection with the accompanying drawings in which like reference characters refer to the same parts throughout the different views, and in which,

Fig. 1 is a view of the stove and oven when in collapsed and packed condition;

Fig. 2 is a perspective view of the stove with the legs extended and the oven portion partially unfolded;

Fig. 3 is a perspective view showing the oven in operative position on and above the stove casing with the front door of the oven in raised position;

Fig. 4 is a perspective view of the stove with certain of the oven parts arranged to form a wind shield;

Fig. 5 is a view of the stove with the oven disposed in its rearward position, another position of the parts being indicated in dotted lines;

Fig. 6 is a perspective view on an enlarged scale showing the wind shield supporting member and other parts secured to the stove casing, certain parts being shown in different position in dotted lines;

Fig. 7 is a vertical section taken through the top of the stove casing and oven when in collapsed and packed condition, said section being taken substantially at the position indicated by line 7-7 in Fig. 1, as indicated by the arrow;

Fig. 8 is a perspective view of the heat distributing plate used;

Fig. 9 is a vertical section taken substantially on the line 9-9 of Fig. 8, as indicated by the arrows; and

Fig. 10 is an enlarged view of a portion of Fig. 9.

Referring to the drawings, a camp stove of the collapsible type is disclosed which comprises the stove containing casing 11 in the upper parts of which is disposed a grid 12 hinged at its rear sides with lugs or clips 13 secured to the rear of the casing 11. The casing 11 has a stove secured therein with the burners 12^a disposed below grid 12. The casing 11 is supported on legs 14 which swing about the pivot arms 14^a journaled in clip brackets 15 secured to the bottom of casing 11 and which have curved arms 14^b adapted to extend through holes 11^a in the bottom of casing 11 adjacent the sides thereof whereby the legs 14 may be swung into the casing, as shown in Fig. 1, or may be extended to support the casing, as shown in Fig. 2, said curved arms 14^b having notches 14^c adjacent one end adapted to snap into engagement with the sides of the holes 11^a, said arms being resilient so that they can be readily disengaged. The casing 11 is provided on one side with a swinging bail handle 11^e by which the device is carried when in collapsed condition.

The stove thus far described may be quite similar to that shown in applicant's prior Patent No. 1,387,152, granted August 12, 1921, reissued April 7, 1922, No. 15,325.

In accordance with the present invention, a collapsible and movable oven is provided for the stove and while this oven may take various forms, in the embodiment of the invention illustrated the same is shown as comprising a rectangular plate 16 having ears 18 thereon hinged about the rod 17 extending along the rear top edge of the casing and held by substantially cylindrical portions 11^b of the casing extending therearound. The plate 16 is shown as having its edges 16^a folded inward to form a bead, which bead is slotted at spaced points to provide spaced pintles about which extend at the ends of said plate the ears 19^a secured to rectangular plates 19, which latter plates are thus hinged at each end of plate 16, said plates 19 being shown as having their upper and lower edges 19^b folded inwardly. The plates 19 are provided with a row of holes 19^c adjacent their lower edges, which form draft holes and certain of which are used for a purpose to be later described. The plates 19 also have pivoted to their outer sides adjacent their upper corners flat bars or rods 28, which bars or rods may be swung into the position shown in Figs. 3 and 5. The plate 16 has spaced ears 16^a secured thereto at its outer longitudinal edge which extend through slots formed in the edge of a plate 20 also of rectangular shape and of substantially the same length as plate 16, which plate 20 has an inwardly extending flange 20^a of comparatively small height extending across its ends. The outer edge of plate 20 is provided with spaced slots 20^b through which extend the substantially cylindrical ears 21 which also extend through slots 22^a formed in a strip 22. Another rectangular plate 24 has slots 24^a formed in its inner edge corresponding to the slots 20^b and substantially cylindrical ears or clips 23 extend through the slots 24^a and through the slots 22^a in the strip 22. The plate 24 also has inwardly extending flanges 24^b at each end and said plate is illustrated as having its front edge rolled inward over a wire and slotted at its central portion to receive an operating handle tongue 25. Plate 24 also has secured therethrough substantially midway thereof, downwardly extending clips 26 which are somewhat resilient and adapted to co-operate when the device is in collapsed condition with pins 27 projecting from the ends of casing 11. Pins 27 are carried at the upper ends of resilient strips 28^a secured at their lower ends to the inside of casing 11. The casing 11 has a bracket 29 secured at each end provided with spaced ears in which is journaled a rod 30, the lower end 30^a of which is bent at a right angle and the upper end 30^b of which

is also bent at a right angle and formed with a hook 30^c at its outer end. The rods 30 can be lifted in brackets 29 and swung outwardly across the top of the casing, as indicated in dotted lines in Fig. 6, and as shown in Fig. 4, said rods, when the wind shield is not in use being disposed as shown in Fig. 6. The casing also has pivoted at its end a flat strip 31 having a tongue 31^a cut and struck up therefrom on its inner side. 75

A heat distributing plate 32 is provided made from a rectangular piece of sheet metal having its longitudinal edges 32^a bent downwardly and somewhat inwardly and provided along its ends with rows of holes 32^b. Said plate also has ears 32^c cut therefrom and bent downwardly in spaced relation adjacent each end thereof and these ears have pivoted therein at each end of the plate, a bail 33 formed from a small rod or wire, these bails carrying on their lower portion, spaced ears 34^a secured to a smaller rectangular plate 34. The plates 32 and 34 are thus pivotally connected for relative swinging movement, as indicated in Fig. 9. 90

When the device is in collapsed condition the parts are disposed as shown in Figs. 1 and 7. The plates 19 are folded inwardly in overlapping relation against the inner side of plate 16, the bars 28 at this time being in the position shown in Fig. 3, relative to plate 19. The plates 19 and 16 are then folded about the pindle rod 17 down onto the grid 12. Plate 20 is then folded down on top of plate 16, said plate extending rearwardly, as indicated in Fig. 2, and as shown in Fig. 7. The plate 24 is then folded forwardly and down on top of plate 20. The flanges 20^a and 24^a, together with the strip 22, will now form the sides of a substantially closed chamber, the bottom of which is formed by plate 20 and the top by plate 24. The distributing plate 32 is swung down or in close relation to the plate 34 and these plates are disposed in said closed chamber, as shown in Fig. 7. The parts are thus very neatly and compactly folded down on the casing 11 and grid 12 and occupy very small space. The clips 26 can now be engaged over the pins 27 and will, owing to their resiliency, remain in engagement with said pins. The casing and collapsed oven can thus be easily transported and may be carried by the handle 11^c. 110

When it is desired to use the oven for baking purposes, the clips 26 will be sprung and released pins 27 being pushed inwardly. The plate will be swung upwardly from grid 11 about pindle 17. The grid 12 will now be lifted and strips 31 swung to vertical position, as indicated in dotted lines in Fig. 6. It may be mentioned that the strips 31 when in vertical position rest against the inner side of the flange 11^a on which the grid 12 rests. The plates 19 are now swung 120

outwardly and slightly raised and then lowered with their edges between strips 31 and tongues 31^a. The plate 16 will now be held in vertical position and plate 20 will 5 be swung over the plates 16 and 19, the flanges 20^a extending along the outer sides of plates 19. The plate 24 will now depend at the front of plate 20 and the flanges 24^b will extend along the outer front sides of 10 the plates 19. A closed rectangular oven is thus formed which is disposed over and supported on the casing 11. The stove in casing 11 comprises burners 12^a below grid 12 and in order to distribute the flame from 15 these burners evenly the device shown in Fig. 8 is placed in the oven. Plate 34 rests on grid 12 and plate 32 fits snugly between the plates 19 so that it is held in vertically spaced relation to the plate 34, the bail mem- 20 bers 33 being substantially vertical. The oven can now be used for baking any kind of baked articles and a very efficient oven is provided. It will be noted that the plate 24 can be swung upwardly and rearwardly 25 on top of plate 20 so that the front of the oven may be left open. This is sometimes desirable when it is merely wished to warm up certain articles of food, and plate 24 then forms a convenient shelf on top of the 30 oven.

If it is desired to use the oven as a warming oven, the same can be swung rearward bodily about rod 17 and the bars 28 swung down to contact the supporting surface, as 35 shown in Fig. 5. A convenient warming cabinet or oven is thus formed and articles may be set on top of the same which is formed by plate 24. If desired, the plates 20 and 24 may be folded rearwardly into 40 the position indicated in dotted lines in Fig. 5, the plate 20 being then supported in horizontal position by the plate 24, the latter acting as a leg. A wide shelf is thus formed which may be used to support various articles used in preparing a meal. 45

If it is desired to use a wind shield with the stove, which is often necessary when there is considerable wind, the rods 30 are lifted and swung outwardly, as shown in 50 Figs. 4 and 6. The plates 19 are then swung outwardly in diverging relation, as shown in Fig. 4 and hooks 30^c engaged through the holes 19^c, as shown in Fig. 4. Plates 19 and 16 are thus held in vertical 55 position and an efficient wind shield is provided for the stove. When the parts are in the position shown in Fig. 4, the plates 20 and 24 merely hang down in the rear of plate 16. It should be particularly noted 60 that plates 16, 20 and 24 are connected by a double hinge, that is, these plates can swing substantially through 360 degrees. The plate 20 can thus be folded backwardly when it is disposed in its collapsed position, and, 65 as stated, plate 24 can be folded back on top

of the oven. As before stated, the members 30 and 31 swing inside of casing 11 when the device is in collapsed and packed condition.

From the above description it is seen that 70 applicant has provided an extremely simple and efficient oven structure for a folding camp stove. The device can easily and quickly be arranged in a plurality of positions, each of which has great utility and 75 the whole device can be easily and quickly collapsed into small space and arranged for transportation. The device is quite simple and easily made from simple material which is readily procured. The device has been 80 amply demonstrated in actual practice and found to be very successful and efficient and the same is being commercially made and marketed.

It will, of course, be understood, that 85 various changes may be made in the form, details, arrangement and proportions of the parts without departing from the scope of applicant's invention, which, generally stated, consists in a device capable of carrying out the objects above set forth, in the novel parts and combinations of parts disclosed and defined in the appended claims. 90

What is claimed is:

1. A camp stove structure comprising a 95 unit having in combination a casing having a top edge, a plate hingedly connected to said edge, a series of plates hingedly connected along adjacent edges and to said plate, all of said plates forming an articulated unit constituting five sides of a rectangular oven so as to be supported either on top of said casing and vertically alined therewith or disposed at the rear thereof, said plates being collapsible into flat position on top of said casing with two of said plates disposed beneath said first mentioned plate and two disposed above said plate. 100

2. A camp stove structure having in combination, a burner-containing casing, a collapsible oven comprising a plurality of plates hingedly connected, forming an articulated unit and forming five sides of a rectangular oven, one of which is hinged to said casing and adapted to form either 105 a wind shield section or the rear wall of said oven, and a plate hinged to each end of said plate, said latter plates having means for holding them in diverging relation to form sections of said wind shield or to be arranged in substantially parallel relation to form the end walls of said oven. 115

3. A camp stove structure having in combination, a burner-containing casing, an oven comprising a plurality of hingedly connected plates adapted to be arranged to form a closed oven or to be collapsed in flat superposed condition on said casing, a pair of said plates having flanges at their opposite edges adapted to form a flat chamber when 120 125 130

in collapsed position and a collapsible heat distributing device adapted to be disposed in collapsed condition in said chamber.

4. A camp stove structure having in combination, a burner-containing casing, a collapsible oven comprising a plurality of plates hingedly connected and forming five sides of a rectangular oven including a rectangular plate hinged along one edge to the rear side of said casing, a plate hinged at each end of said first mentioned plate, said first mentioned plate being adapted to be disposed in vertical position with said second mentioned plates at its ends diverging forwardly in vertical position, and means for supporting said second mentioned plates in said position, said means being adapted to swing into said casing and be disposed beneath the top thereof when in inoperative position.

5. A camp stove structure having in combination, a casing having burners secured therein, a collapsible oven comprising a plate hinged to one edge of said casing, a second similar plate hinged to the opposite edge of said plate and adapted to swing through substantially 360 degrees about said edge, a third plate hinged to the edge of said latter plate opposite its connected edge and adapted to swing through substantially 360 degrees, and a pair of plates hinged, respectively, at each end edge of said first mentioned plate so that said plates may be arranged to form a rectangular oven and said second plate may be folded backwardly on top of said first mentioned plate and said third plate may be folded forwardly on said second plate when said plates are in collapsed condition.

6. The combination with the casing of a camp stove, of an oven structure comprising a substantially rectangular plate hinged to the rear top edge of said casing, a similar plate hinged to the opposite side of said plate, a rectangular plate hinged to the side opposite the hinged side of said last mentioned plate, and a rectangular plate hinged to each end of said first mentioned plate, said latter plates being adapted to be held in diverging relation to form wind shields at each side of said casing, or to be disposed in substantially parallel relation at the ends of said other plates to form the ends of a closed rectangular oven and means for holding said latter plates in diverging relation.

7. The combination with the burner-containing casing of a folding camp stove, of a

collapsible oven comprising a plurality of connected plates, said plates forming an articulated unit constituting five sides of a rectangular oven, one of which is hinged to said casing, two of said plates being hinged to said plate and adapted to be held in substantially parallel position to form the ends of said oven, but being adapted to diverge in vertical position at the ends of said casing to form a wind shield, and means carried by said casing for holding said plates in said latter position.

8. The structure set forth in claim 7, said last mentioned means comprising hooks pivoted on vertical axes at each side of said casing and adapted to be swung outward of said casing to support said plates or to be swung inward of said casing and moved beneath the top thereof.

9. A folding camp stove structure having in combination, a burner-containing casing, means for supporting said casing, a collapsible oven carried by said casing including a rear plate and end plates connected respectively to each end thereof, means at each end of said casing for supporting and holding said end plates in operative position, said second mentioned means being movable to inoperative position within said casing.

10. The structure set forth in claim 9, said second mentioned means comprising flat pieces pivoted to the inner end surfaces of said casing and having tongues extending therefrom and substantially parallel thereto, said pieces being swingable into upright operative position to extend above the top of said casing or to inoperative position within said casing.

11. A folding camp stove structure having in combination a burner containing casing, a collapsible oven comprising a plurality of hingedly connected plates forming an articulated unit and five sides of said oven, one of which plates is hinged to the rear side edge of said casing and is adapted to form the back of the oven or the front portion of a horizontal shelf, a second plate hinged to said first plate and adapted to form either the top of the oven or the rear portion of the horizontal shelf, a third plate hinged to said second plate and adapted to form either the front of the oven or a rear support for the horizontal shelf, and side plates hinged to said first plate and adapted to form the sides of said oven.

In testimony whereof I affix my signature.
HANS C. HANSON.
